UNITED STATES PATENT OFFICE

156,985

EDIBLE DISH

Frank Wesley Moffett, Jr., Gates, N. Y.

Application December 13, 1946, Serial No. 135,476

Term of patent 14 years

(Cl. D8—1)

To all whom it may concern:

Be it known that I, Frank Wesley Moffett, Jr., a citizen of the United States of America, residing at Gates, in the county of Monroe and State of New York, have invented a new, original, and ornamental Design For an Edible Dish, of which the following is a specification, reference being had to the accompanying drawing, forming a part thereof.

In the drawing:

Fig. 1 is a plan view of an edible dish, showing my new design, and

Fig. 2 is a view in side elevation.

I claim:

The ornamental design for an edible dish, as shown.

FRANK WESLEY MOFFETT, JR.
